UNITED STATES PATENT OFFICE.

WILLIAM GEORGE DUNHAM, OF SCHENECTADY, NEW YORK, ASSIGNOR TO WEBER ELECTRIC COMPANY, OF SCHENECTADY, NEW YORK, A CORPORATION OF NEW YORK.

DESIGN FOR A CHAIN PENDANT.

Application filed January 29, 1927. Serial No. 20,538. Term of patent 14 years.

To all whom it may concern:

Be it known that I, WILLIAM G. DUNHAM, a subject of Great Britain, residing at Schenectady, in the county of Schenectady and State of New York, have invented a new, original, and ornamental Design for Chain Pendants, of which the following is a specification, reference being had to the accompanying drawing, forming part thereof.

Fig. 1 of the drawings is a view in side elevation of a chain pendant showing my new design.

Fig. 2 is a top plan view of the same. The drawings are on an enlarged scale.

I claim:

The ornamental design for a chain pendant, as shown.

WILLIAM GEORGE DUNHAM.
